ATTORNEY

UNITED STATES PATENT OFFICE.

HOWARD A. ROGERS, OF ATLANTA, GEORGIA, ASSIGNOR OF ONE-HALF TO SAMUEL SHIELDS, OF ATLANTA, GEORGIA.

OVEN ATTACHMENT.

1,230,926.

Specification of Letters Patent. Patented June 26, 1917.

Application filed April 6, 1916. Serial No. 89,426.

To all whom it may concern:

Be it known that I, HOWARD A. ROGERS, a citizen of the United States, residing at Atlanta, in the county of Fulton and State 5 of Georgia, have invented certain new and useful Improvements in Ovén Attachments, of which the following is a specification.

This invention has relation to heating appliances, and the nature and objects thereof 10 will be readily apparent to those skilled in the art to which it appertains, in the light of the following explanation of the accompanying drawings, illustrating what I now believe to be the preferred embodiment, or 15 mechanical expression, of my invention from among other forms within the spirit of the invention and the scope of the appended claims.

However, an object of the invention is to 20 provide a portable oven which is attachable to heating stoves, wherein an oven does not form a portion of the permanent structure of the stove.

Another object of the invention is to provide 25 in an oven of the character described, means whereby the gases issuing from the stove may be directed around the oven to heat the same or if desired may be provided with a direct passage for the gases to the 30 smoke pipe.

In addition to the foregoing my invention comprehends improvements in the details of construction and arrangement of parts to be hereinafter described, and particularly 35 pointed out in the appended claims.

In the accompanying drawings in which similar and corresponding parts are designated by the same reference characters throughout the several views in which they 40 appear,

Figure 1, is a view in side elevation of a conventional type of heating stove showing the application thereto of my improved oven,

Fig. 2, is a plan view of the oven partly 45 broken away, and the stove,

Fig. 3, is a central vertical detail section and

Fig. 4, is a vertical detail section through the damper.

With reference to the drawings 1 indicates a conventional heating stove having a boss 2 at its upper portion to which the smoke pipe is usually connected. My invention comprises a substantially rectangular 50 outer casing 3 provided with an inlet 4 at its

lower portion which is surrounded with a depending flange 5 for engagement within the boss 2 of the stove. An outlet opening is provided at the upper portion of the casing, and preferably in vertical alinement 60 with the opening 4 for connection with a smoke pipe 6.

An inner casing 7 is provided within the casing 3, and is spaced from the top, bottom, and longitudinal sides, of the outer casing, 65 but is connected thereto at either end. The top of the inner casing is formed with a flange 8 which is secured to the front wall of the outer casing and is provided with an aperture 9 disposed directly beneath the 70 smoke pipe 6. A damper 10 is disposed above the opening 9 for normally closing the same, and is actuated by a rod 11 which extends through the casing and is provided at its terminal outside the casing with a 75 handle 12.

One end of the outer casing is apertured for registration with the open end of the inner casing so as to provide an entrance thereto; the inner casing therefor constitutes the oven. A closure 13 is hingedly mounted adjacent the aperture in the end of the casing for normally closing the oven. A door 14 is provided for closing an opening 15 in the front wall of the outer casing, and a 80 securing element 16 is mounted upon the interior of the outer casing and is provided with a hook portion 17 for extending through the inlet opening 4, to engage the under surface of the roof of the stove, for 85 securing the oven thereto. As an additional means of fastening the oven to the stove rods 18 are provided for engagement with eyes 19 upon the oven, and within apertures at the base portion of the stove. The lower 90 terminals 20 are threaded, and provided with nuts 21.

When the oven is to be heated, the damper 10 is in position so as to cover the opening 9, and the heated gases from the stove are 100 forced to travel horizontally toward the rear of the casing then vertically to the upper portion of the casing, and then horizontally again toward the exit opening. In this manner the sides of the oven are heated, and articles of food placed within the inner casing are cooked, or their temperature maintained according to the extent to which the opening 10 is closed.

If the temperature of the oven is to be 119

low, or if the draft of the stove is to be accelerated, the damper 10 is thrown back so as to entirely uncover the opening 9, whereupon the heated gases may rise into and through the space between the front wall of the casing, and the inner casing to the opening 9, and thence directly to the smoke pipe.

Various ways of constructing my invention will occur to those skilled in the art, 10 and I therefore reserve the right and privilege of changing the form of the details and otherwise altering the arrangement of parts, without departing from the spirit of the invention or the scope of the appended claims. 15

Having now described my invention, what I claim as new and desire to secure by Letters Patent is:—

1. An oven attachment for stoves, including an outer rectangular casing having vertically alined outlet and inlet openings formed in the top and bottom sides respectively thereof and adjacent the front wall, an inner casing forming an oven secured to 20 the end walls of the outer casing and spaced from the remaining walls, a flange formed by a horizontal extension of the top side of the inner casing, said flange having an opening in alinement with the first mentioned 25

opening, and a damper for varying the aperture of said opening. 30

2. An oven attachment for stoves including an outer casing having inlet and outlet openings formed in its bottom and top sides respectively, an oven casing within the outer casing spaced therefrom to provide a channel for the passage of heated air, a flange 35 formed around the inlet opening for insertion in the smoke outlet of a stove, one vertical wall of the outer casing having an opening formed therein adjacent the inlet opening, a door forming a closure for said vertical wall opening, and a hook member pivoted to said vertical wall and depending behind the opening formed therein and into 40 the inlet opening of the outer casing for insertion into the smoke outlet of the stove, and for engagement under the top side of the stove, to hold the attachment in place, said hook member being adjusted through 45 the opening in the vertical wall. 50

In testimony whereof I affix my signature in presence of two witnesses.

HOWARD A. ROGERS.
